UNITED STATES PATENT OFFICE.

ARSENIOUS R. PLOPPERT, OF SHENANDOAH, PENNSYLVANIA.

SAFETY-VALVE FOR STEAM-BOILERS.

SPECIFICATION forming part of Letters Patent No. 762,085, dated June 7, 1904.

Application filed March 5, 1904. Serial No. 196,662. (No model.)

To all whom it may concern:

Be it known that I, ARSENIOUS R. PLOPPERT, a citizen of the United States, residing at Shenandoah, in the county of Schuylkill and State 5 of Pennsylvania, have invented certain new and useful Improvements in Safety Devices for Steam-Boilers, particularly for boilers and hot-water tanks used in connection with kitchen ranges and stoves, of which the following is a 10 specification.

This invention relates to safety devices for steam-boilers, and particularly to that class adapted to be connected to boilers and hot-water tanks used in connection with kitchen 15 ranges and stoves.

The object of the invention is to provide a simple and improved device of this character which shall be thoroughly automatic in its 20 operation. Furthermore, the object of the invention is to provide a device having a piston-rod with a piston-head secured upon both ends of the rod and so arranged that the piston-rod will open and close the safety-valve.

Furthermore, the object of the invention is 25 to provide a safety device of the character described of simple and inexpensive construction and which is adapted to be readily connected to boilers of various construction.

My invention, stated in general terms, consists of a piston-rod provided with a piston-head at each end, cylinders provided in the extension ends of the cold and hot water pipes, and rod connection with the crank-arm of the safety-valve.

The nature and scope of my invention will be more fully understood from the following description, taken in connection with the accompanying drawings, forming part of this specification, wherein like characters denote 30 corresponding parts in both views, and in which—

Figure 1 is a view in elevation of my invention. Fig. 2 is a view in elevation of my invention connected to a boiler and having parts 45 broken away to show the inner construction of the same.

In the drawings, 1 denotes an ordinary hot-water boiler or hot-water tank, and 2 the cold-water supply-pipe to the boiler. The hot- 50 water or outlet pipe 3 is provided with a T-

shaped connection, so that the house-supply pipes may be attached thereto.

I provide my invention with a cold-water pipe 4, having near its outer end a port which is closed by a check-valve 5, said check-valve 55 preventing the hot water or steam from entering the cold-water pipe when the pressure of the steam becomes greater than that of the cold water. The cold-water pipe is provided with a short extension 6, which extends a pre-determined distance beyond the port and safety-valve. In this extension I provide a piston-head 7, suitable bushing and packing 8, a threaded cap 9 being secured over the extension to form a water-tight cylinder, the 60 central portion of the cap being provided with an aperture. Commencing at the check-valve 65 the cold-water pipe extends in an approximately semicircular shape, the opposite end of which is straight and provided with screw-thread which permits the pipe to be coupled to the cold-water pipe of the boiler.

The hot-water or steam outlet-pipe is formed for a predetermined distance at one end integrally with the straight end of the cold-water 70 or inlet pipe. The steam-pipe is bent at a right angle, and the vertical portion 10 I provide at its outer end with a safety-valve 11, said safety-valve being provided with a crank-arm 12. At the base of the vertical extension 75 10 of the steam-pipe I provide an extension 13, which serves as the cylinder for the piston-head 14. This extension is also provided with a suitable bushing, a packing, and cap.

The piston-heads 7 and 14 are connected by 80 a piston-rod 15. On top of the circular portion of the cold-water-inlet pipe I provide a pivot-pin 16. This pin is located about midway the two ends of the pipe. A connecting-rod 17 is pivoted on the pivot-pin, and this 85 rod has ears formed at each end, one end straddling the piston-rod and having suitable connection therewith, and the opposite end, which is also provided with ears, is connected to a rod 18, the last-named rod being connected 90 with the crank-arm of the safety-valve.

From the above description it will be seen that I employ both the pressure of the cold water and steam to operate the device. When the steam-pressure is greater than the mean 95 100

pressure of the cold water, the piston-head 14 is forced against the end of its cylinder, and the safety-valve, through the medium of the piston-rod 15, connecting-rod 17 and 18, is 5 opened and the steam allowed to escape. After sufficient amount of steam has escaped to lower the steam-pressure below that of the cold-water pressure the cold water pressing against the piston-head 7 pushes the piston- 10 head 7 back against the packing and bushing, and the safety-valve is closed through the same medium which operated to open it.

The construction, operation, and advantages, it is thought, will be understood from the foregoing 15 description, it being noted that various changes may be made in the proportion and details of construction without departing from the scope of the invention.

Having fully described my invention, what 20 I claim as new, and desire to secure by Letters Patent, is—

1. In a safety device of the character described an inlet and an outlet pipe, a check-valve seated in the inlet-pipe, a safety-valve 25 provided at the end of the outlet-pipe, cylinder extensions to the pipes, a piston rod and heads and means for operating the safety-valve substantially as shown.

2. In a safety device for boilers, an inlet 30 and an outlet pipe having cylinders therein,

a piston-rod having a piston-head at each end, rods connecting the piston-rod and safety-valve substantially as described.

3. In a safety device of the character described, an inlet and an outlet pipe, having cylinders formed in their end extensions, piston-heads adapted to fit the cylinders and a piston-rod connecting the piston-heads and rods connecting the piston-rod with the crank-arm of the safety-valve as and for the purpose described. 40

4. In a safety device for steam-boilers, an outlet and an inlet pipe, cylinders formed in the extension ends of the inlet and outlet pipes, said cylinders provided with suitable bushing 45 and packing, piston-heads adapted to reciprocate in the cylinders, a piston-rod connecting the piston-heads, a pivot-pin secured to the cold-water pipe, a rod pivoted on the pin and having end connections with the piston-rod 50 and with a second rod, said last-named rod having its opposite end connected to the crank-arm of the safety-valve substantially as and for the purpose described.

In testimony whereof I affix my signature in 55 presence of two witnesses.

ARSENIUS R. PLOPPERT.
